T. J. SULLIVAN, OF ALBANY, NEW YORK.

Letters Patent No. 86,189, dated January 26, 1869.

IMPROVEMENT IN THE CONSTRUCTION OF SAFES.

The Schedule referred to in these Letters Patent and making part of the same

To all whom it may concern:

Be it known that I, T. J. SULLIVAN, of Albany, in the county of Albany, and State of New York, have invented a certain new and useful Improvement in the Construction of Safes; and I do hereby declare that the following is a full and exact description thereof, reference being had to the accompanying drawings, making part of this specification.

Figure 1 is a horizontal section of my improved safe.

Figure 2, a perspective view of the skeleton, removed from place.

Like letters of reference indicate corresponding parts in both figures.

My invention consists in the peculiar construction hereinafter described, whereby the use of hoops or bands is avoided on the outside, and the inside is sustained by a skeleton, embodying great strength.

In the accompanying drawings—

A A A represent plates, forming the sides of the safe, which are made entirely smooth and unbroken on the outside.

B B B represent angle-plates, forming a continuous and connected skeleton, of cubic form, fitting closely inside the outer plating, and fitting the angles, as clearly shown.

C C C represent corner-pieces, fitting inside the corners of the angle-irons.

The parts, thus arranged, are united by riveting the outer plates to the angle-irons, and then passing screws, *a a*, through the plating into the corner-pieces, whereby the parts are closely clamped, as clearly shown in fig. 1.

The screw-holes are simply countersunk in the outer plates sufficiently to receive the screw-heads, (which have no slots,) and the remainder, all the way through, are tapped or threaded, and nuts, *b b*, are attached to the screws on the inside.

In fire-proof work, the ordinary inner lining is applied, and the intervening space filled with cement, or other material. In this case, the back plate of the safe is not applied till the filling is complete, and is

then attached to the angle-irons by screws instead of rivets, as before described.

By this construction, I avoid the heavy, forged, wrought-iron hoops that are ordinarily applied outside of safes, which are not only expensive, but are easily torn off by burglars with suitable tools.

I substitute in place a perfectly-smooth outside, on which no hold can be got by tools. The screw-heads, being dressed down with the surface, and having no slots, and being painted over, are not easily discovered; and, even if found, being made of steel, and threaded through, cannot be drilled out or turned loose. Besides, the riveting of the plates to the angle-arms is an effectual safeguard.

In addition to the above, the angle-irons, united in skeleton-form, fitting exactly the interior of the safe, and stiffened by the corner-pieces C, make a most substantial and effective brace or support to the outer plating of the safe, since every side is stayed all around.

By this simple construction, much labor and many dollars are saved in every safe, while the work is really stronger and more enduring than in any other with which I am acquainted.

I am aware that angle-irons and corner-pieces have before been used in various relations, serving as attachments or stays simply. Such, in themselves, I do not claim. But I am not aware that such parts have ever been united in skeleton-form to produce a complete frame.

What I claim as my invention, and desire to secure by Letters Patent, is—

The special construction of the safe, as herein set forth, viz, with smooth sides A A, united by screws and rivets to an interior skeleton made of angle-irons B B and corner-plates C C, the whole arranged as described, and for the purpose specified.

In witness whereof, I have hereunto signed my name, in the presence of two subscribing witnesses.

Witnesses: T. J. SULLIVAN.
J. A. DAVIS,
W. J. CREELMAN.
